Primary Examiner — Samantha Wood(74) *Attorney, Agent, or Firm* — Jeffrey L. Doyle(57) **CLAIM**

The ornamental design for a faucet as shown and described.

DESCRIPTION

FIG. 1 is a front perspective view of a faucet showing my new design;

FIG. 2 is a rear perspective view thereof;

FIG. 3 is a front elevational view thereof;

FIG. 4 is a left side view thereof;

FIG. 5 is a rear view thereof;

FIG. 6 is a right side view thereof;

FIG. 7 is a top plan view thereof; and,

FIG. 8 is a bottom view thereof.

The broken lines in the drawings illustrating a side sprayer are directed to environment and are for illustrative purposes only, while all other broken lines denote the bounds of the claimed design; the broken lines form no part of the claimed design.
